WICK SUPPORT FOR DEVOTIONAL LIGHTS

Huber H. Root and Karl Rau, Medina, Ohio, as
signors to The A. I. Root Company, Medina,
Ohio, a corporation of Ohio

Application February 20, 1940, Serial No. 319,852

6 Claims. (Cl. 67—21)

This invention relates to the class or type of devotional light device which is exemplified by U. S. Reissue 18,623 to Huber H. Root, October 18, 1932, and particularly to an improvement in wicks for light devices of said type or class.

The type of light device referred to comprises an upright elongated translucent or transparent container for solid fuel which latter supplies a wick disposed centrally of the fuel body and normally supported in central position by the fuel. When the device is used, e. g., as a sanctuary light, the flame is required to burn continuously from initial lighting of it until practically all the fuel is consumed, and during all of this time (seven or eight days), it is essential to the purpose that the flame or light emanating therefrom be clearly observable at a considerable distance away from the device.

The most satisfactory material for the translucent or transparent casing or container for the fuel is glass. This may be a bottle as shown in said reissue patent, Fig. 3, or an open jar. It may be simply a tube. In any case, the glass wall has to be thick enough so that it necessarily absorbs and retains considerable heat. Such retained heat is of great advantage in a light device of said type which is properly designed, because—particularly at the start of the burning period—the retained heat assists greatly in maintaining the glass wall opposite the exposed portion of the burning wick free from solid fuel such as might otherwise obscure the flame and, later, melt and drown the flame. After the critical starting period, there is less likelihood of a rim of solid fuel remaining on the glass wall opposite the flame, because the area of glass exposed to the heat of the flame progressively increases as the fuel is consumed. However, if the temperature outside the casing is relatively high—well above normal, as in hot climates—so much melted fuel stands on top of the solid fuel that the wick becomes unsupported laterally at a distance of several inches from the lighted end which projects above the fuel, and the unsupported portion of the wick is apt to bend until either the flame touches the glass wall or the top of the wick becomes submerged in the melted pool of fuel. If the flame touches the wall, it is likely to crack the glass, and, of course, if the tip of the wick is submerged, the flame is extinguished.

For the above reasons, wicks for the type of lights referred to usually have reinforcing cores or centers which are either combustible or fusible. Such cores are expected to maintain up-

right whatever upper portions of respective wicks become laterally unsupported by solid fuel under abnormal conditions such as mentioned above. Metal wire of low fusion point, for example lead, used as a core, is too soft to hold the otherwise unsupported upper end portion of the wick erect when such unsupported portion attains a length of several inches. Moreover, lead and other metals which will fuse or melt when exposed directly to the heat of a candle flame react with fuels such as commonly used in the light devices, leaving a scummy film on the inside of the casing, which film partially obscures the light of the flame. Combustible stiffening material such as bamboo has been used in attempts to overcome the difficulties experienced with stiffening material which melts off at the wick tip.

Bamboo splint cores or centers for wicks are capable of holding the wicks erect when the solid fuel is melted to unusual depths, but the use of bamboo has several drawbacks. Straight bamboo splints can be obtained only in short lengths, hence bamboo cannot be supplied as a continuous strand during braiding or weaving of the wick threads about the core. Therefore, the splints have to be inserted by hand in hollow braided wicking. This is a slow tedious process and, moreover—because the splints vary in cross-sectional size and shape and in surface smoothness—the wicks, so stiffened, are not uniform because of crowding and stretching of the wick fabric during such insertion of the splints, and the wicks burn irregularly. The combustible centers, such as bamboo, absorb fuel and burn away with the strand part of the wick, adding to the carbon and ash deposit which preferably should be minimized.

It has also been proposed to use fine wire intertwined or interwoven with the wick strands parallel thereto or wrapped helically about the wicking with the idea of stiffening the same. This requires either abrupt kinks or open coils in the wire, and if the wire is sufficiently fine so that oxidation or fusion of the wire occurs by contact with the flame, then the wire, because of its shape, is inherently too flexible to serve the purpose. On the other hand, if the wire is so heavy that, notwithstanding the kinking or coiling of it, it will not oxidize or be consumed when exposed to the flame and will have sufficient stiffness properly to serve the purpose, notwithstanding the coils or kinks, then the carbon and ash cling indefinitely to the wire and cause excessive smoking.

An object of the present invention is to pro-

vide non-consumable reinforcing means for wicks of devotional lights of the type or class identified above and which are sufficiently high or deep so that the wick under certain conditions may become laterally unsupported below the flame for a considerable distance, as several inches, and which reinforcing means cooperates with the casing in a manner to retain the wick in an effective operating position regardless of the depth to which the fuel may be melted and ineffective as a support for the wick.

A further object is to provide a devotional light of said type or class and of upright elongated form and including a translucent or transparent casing, as of glass, functioning as a vessel for maintaining melted fuel in cooperative relation to the wick, irrespective of the depth of such melted fuel, wherein the flame-supporting portion of the wick cannot move so far from the center of the casing as to endanger the casing and cannot become immersed in the melted fuel and drown the flame.

Other objects will be made apparent below.

Referring to the drawing, Fig. 1 is a central vertical sectional view of a devotional light incorporating the invention and prior to lighting the wick; Fig. 2 is a similar view showing the wick lighted and the fuel partially consumed; Fig. 3 is a view similar to Figs. 1 and 2 showing a different type of casing for the fuel, and Fig. 4 is a fragmentary view showing diagrammatically the manner in which the non-consuming reinforce for the wicking may be incorporated with wicking as a continuous operation.

In Fig. 1, a glass casing 1 contains normally solidified fuel 2 and central wick 3. The casing is in the form of a bottle with a gradual restriction 4 and a rim portion 5. A suitable supporting piece 6 for the wick lies on the bottom wall of the bottle so that near the end of the burning period the wick will stand upright when the heat of the flame has melted all the fuel remaining near the end of the burning period. The casing 1 usually is contained in a display cylinder of glass, e. g. "ruby glass," not shown. As indicated in Fig. 4, the wick 3 preferably is made from cotton or other threads or strands 7 which are supplied continuously from bobbins or spools and braided or interwoven about a central strand which is also supplied continuously from a coil. In the illustration, the central strand comprises a non-consumable wire core 10 and constitutes the reinforcing means or stiffener of the present invention. The wire 10, as supplied from a coil, can be straightened by passage through a suitable straightening mechanism before it passes to the region in which it is enveloped by the strands 7 to form the complete wick. Thus the wick has no inherent tendency to bend in any direction when unsupported. The central strand or core 10 is preferably soft stainless steel, in which case it can be a very fine wire, such as from .0056" to .0125". The reinforcing means or stiffener 10 can be much larger, however, irrespective of the kind of metal used. For some uses, the wick material may be woven, twisted or otherwise formed and the stiffener incorporated.

Although copper, aluminum, or ordinary steel wire can be used if the wire is coarse enough, they are not as desirable or as satisfactory. Rubrical lights require beeswax and copper reacts with cerotic acid forming a greenish film on the casing. Iron oxidizes rapidly and, unless a fairly coarse wire is used, an iron or ordinary

steel center warps out of shape and sometimes is wholly consumed by the oxidation at some part of its length. Aluminum wire, unless fairly large, is apt to be destroyed by the heat of the flame or too badly weakened to remain sufficiently nearly erect above the flame to provide a complete solution of the problem or the fulfilment of all the objects of the invention. Synthetic materials which are not reducible by or combustible in the heat of a candle flame may also be used to fulfil all the purposes hereof, providing the same can be made in continuous strand form, be fairly stiff, and remain substantially straight under the operating conditions described. One such material is known as synthetic mica (Alsimag). It is believed that this is not available as a commercial product at the present time.

Referring further to the drawing, it will be noted that so long as the fuel is solid as in Fig. 1, and, after lighting, so long as only a shallow pool of melted fuel occurs at the top of the solid fuel, there is no danger of the usual wick being unsupported and causing the flame to become drowned or to come into contact with the glass casing.

When, however, the pool becomes several inches deep, (see 8, Figs. 2 and 3), as it does if outside temperature is high and no means are provided to cool the casing, the ordinary wick can bend as at 3a, Fig. 2, with resultant submergence of the tip. Where the pool is excessively deep, say five or six inches, the bending of the wick causes the glass to be cracked as explained above.

The stiffener 10 of the present wick normally remains nearly erect, as shown in full lines, Fig. 2, even though the pool 8 is several inches deep. If it does bend over, the bending is limited, as indicated at 3b, Fig. 2, by engagement of the stiffener 10 with the casing wall which, assuming the casing is in the form of a bottle, is at the restricted neck. Essentially the same result is attained when no restriction is present when the core is in an open jar 15, as indicated at 3d in Fig. 3. Special means may, of course, be used to maintain the upper end of the stiffener 10 more nearly centrally of the casing. A cap 16 which is centrally apertured as at 17 for entrance of air and/or exit of products of combustion is indicated diagrammatically in Fig. 3 and is illustrative of means separate from the glass casing for engagement with and support of the bared end of the stiffener 10 of the wick when such is required by consumption of fuel to a point well below the top, or melting of the fuel to any distance down from the top. The position of the bared stiffener when it engages the inner rim of such a device as the cap 16 is indicated at 3c.

The reinforcing means or stiffener should have a smooth surface and the same should remain smooth after subjection to the heat of the flame, and the reactions set up by the burning of the wick, so that residual products such as carbon and ash will drop off below the flame tip.

It is preferable that the reinforcing means or stiffener be such that it is not oxidized when subjected to the heat of the flame. Oxidation would destroy the smooth and shiny surface. A stainless steel wire with the usual wick material braided thereabout and intimately enveloping the wire meets all of the requirements hereinbefore described and the resultant wick is well suited for its intended purposes, and particularly for use in connection with fuel bodies comprising

essentially beeswax and mineral oil, the beeswax being fifty per cent or more of the total.

We claim:

1. A combined candle wick and stiffener for the purposes described and comprising a self sustaining tube of combustible pliable material which tube is incapable of supporting itself without bending when extending upwardly free from lateral support for a height of several inches, and a supporting substantially straight smooth surfaced core member of material which will not become consumed or melted when in contact with a candle flame and of small cross section relative to the tube and substantially coextensive endwise therewith, said member being embedded in the pliable material for substantially the entire length of said tube and being capable, in itself, of supporting itself and the tube substantially without bending when the member is resting on one of its ends and is leaning against a support at its other end.

2. A combined candle wick and stiffener for the purposes described and comprising an outer tube of combustible pliable material incapable of self support in upright position without bending and a substantially straight stiffening core of stainless steel of small cross section relative to the tube and extending substantially centrally thereof for substantially the entire length of said tube.

3. In a light for the purposes described and including an elongated upright generally translucent casing, a quantity of fuel therein, and a wick in said fuel and extending generally axially of the casing out of contact therewith for substantially the entire length of the wick, a non-fusible, non-combustible substantially straight stiffener of small cross section relative to the cross section of the wick embedded in the wick centrally thereof and extending lengthwise of the wick for its full length, said stiffener being of sufficient length to be supported at its lower end at or near the bottom of the casing while the stiffener is exposed by burning away of the upper end portion of the wick and is leaning against a wall portion of the casing at its upper end, and being capable, in itself, while in said leaning condition and free from the wick at its upper end, of supporting a flame on the upper end of the remaining portion of the wick out of contact with the casing wall.

4. In a light of the general character described and including an elongated upright generally translucent casing, a normally pliable wick extending generally axially of the casing and normally out of contact therewith for substantially the entire length of the wick, and a body of fuel

within the casing and surrounding the wick, a substantially straight non-fusible stiffener forming a core for the wick and of sufficient length relative to the casing to extend from near the center bottom portion of the casing to the upper portion of the side wall of the casing, said stiffener being capable, in itself, of supporting the wick while the wick is ignited and while the stiffener is leaning against the casing at the upper

10 wall portion of the casing upwardly beyond the burning portion, whereby the burning portion of the wick is constrained by the stiffener to a position above the level of the fuel and out of contact with the casing.

15 5. A devotional light comprising a translucent casing capable of retaining melted fuel in contact with wall portions of the casing through which light from a flame inside the casing would normally be visible, a solid fuel body and wick 20 in said casing, the wick being normally retained by the fuel body centrally of the casing, said fuel body containing a substantial percentage of beeswax, and a stiffening core for the wick substantially coextensive therewith which core is non-fusible and non-consumable in the heat of the 25 flame, so that the core can support the unburned portion of the wick as by contact with the casing a considerable distance upwardly beyond the flame, and which core is chemically inert with respect to said fuel when heated by the flame, whereby the visibility of the flame through the casing wall will not become impaired by deposit of reaction products on said casing wall.

30 6. In a light of the general character described and including an elongated upright casing having a translucent side wall, a normally pliable wick extending generally axially of the casing, and a body of fuel within the casing and surrounding the wick, a non-fusible and non-combustible stiffener operatively connected to the wick for its full length and capable, in itself, of supporting the wick while the wick is ignited and while the stiffener rests at its lower end at or 35 near the bottom of the casing centrally thereof and is angularly disposed to the axis of the casing, and means on the casing and engageable with the upper end portion of the stiffener materially inwardly toward the center of the casing from said side wall and operative when so engaged to constrain the stiffener to a position at such an angle to the axis of the casing that the flame on the wick will be spaced from said side wall during substantially the entire burning 40 operation of the light notwithstanding fluidity 45 of the fuel around the wick.
